Attorneys

UNITED STATES PATENT OFFICE.

HERMAN WARLICH, OF RACINE, WISCONSIN.

ALARM.

SPECIFICATION forming part of Letters Patent No. 394,895, dated December 18, 1888.

Application filed October 8, 1888. Serial No. 287,512. (No model.)

To all whom it may concern:

Be it known that I, HERMAN WARLICH, of Racine, in the county of Racine, and in the State of Wisconsin, have invented certain new and useful Improvements in Alarms; and I do hereby declare that the following is a full, clear, and exact description thereof.

My invention relates more particularly to burglar-alarms; and it consists in certain peculiarities of construction and combination of parts to be hereinafter described with reference to the accompanying drawings, and subsequently claimed.

In the drawings, Figure 1 represents an elevation of my device in operative position with relation to a window; Fig. 2, a horizontal section taken on line 2 2, Fig. 1; and Fig. 3 a vertical transverse section taken on line 3 3, Fig. 1.

Referring by letter to the drawings, A represents the upper and B the lower sash of a window. Secured to the top rail of the lower sash, B, by screws b, or other suitable means, is the base-plate C of my device, and pivotally connected to this base is a standard, D, that has a weighted upper end, d, and is provided at its lower end with a projection, e, that carries a lug, f, the latter being acted on by a spring, E, held upon the pivot-bolt g that unites said base-plate and standard.

At about the center of the weighted and pivoted standard D is a stud, F, having a reduced portion, h, that is preferably screw-threaded in said standard, as best illustrated in Fig. 3. The reduced portion h of the stud F serves as a bearing for a friction-wheel, G, that is preferably provided with a tire of rubber or other elastic material, and arranged upon the outer side of this wheel is a series of radial lugs, i, having beveled faces.

Rigidly connected to the weighted upper end of the standard D is a spring-wire, H, having a bend, j, that comes in the path of the lugs i on the friction-wheel G, and another bend, k, that passes around and under the stud F. Secured to the bend k of the spring-wire H is a hammer, I, that is designed to strike a gong, J, secured to the stud F by means of a set-screw, m, or other suitable means.

The extreme lower end of the standard D

is rounded or beveled off, as shown at n, and when said standard is swung outward on its pivot g this rounded or beveled portion comes against a stop formed by a flange, o, on the base-plate C.

In the operation of my invention the standard D is swung on its pivot g, so as to bring the rim of the friction-wheel G against the side rail of the upper sash, A, and the spring E is placed under the lug f on said standard, so as to hold the latter in the position to which it has been adjusted, the weighted end of said standard aiding the spring in the accomplishment of this result. Now if the lower sash, B, be raised the frictional contact of the wheel G with the opposing side rail of the upper sash, A, will cause said wheel to rotate in the direction of the arrow, Fig. 1, and thus the lugs i on the wheel will operate upon the bend j in the spring-wire H and cause the hammer I thereon to strike a successive number of blows upon the gong J. If the upper sash be lowered, the same operation will take place; but when the lower sash is being drawn down or said upper sash raised the wheel G will rotate in a direction opposite to that already described and the beveled faces of the lugs i on said wheel will slip past the bend j in the spring-wire H, and thus the latter will not be actuated. To throw the wheel G out of contact with the side rail of the upper sash, A, the spring E is withdrawn from under the lug f, and the standard D is swung back on its pivot g, said standard being held in the latter position by its weighted upper end.

Although I have more particularly described my invention in connection with a window, it is obvious that the device may be otherwise employed, it being obvious that said device may be arranged to have the friction-wheel act in conjunction with any movable part, or travel along a stationary part, and in either case the movement will be indicated by the ringing of the gong.

Having thus fully described my invention, what I claim as new, and desire to secure by Letters Patent, is—

1. An alarm that comprises a pivoted and weighted standard, a friction-wheel having its bearing on the standard provided with a

series of radial lugs, a spring-wire carrying a hammer and arranged to be actuated by said lugs and a gong arranged to be struck by the hammer, substantially as set forth.

5 2. An alarm that comprises a pivoted and weighted standard, a friction-wheel having its bearing on the standard provided with a series of radial lugs beveled upon their outer faces, a spring-wire carrying a hammer and 10 arranged in the path of the lugs, and a gong arranged to be struck by the hammer, substantially as set forth.

3. An alarm that comprises a base-plate, a weighted standard pivotally connected 15 thereto, a friction-wheel journaled to the standard and provided with a series of lugs, a spring-wire carrying a hammer and arranged to be actuated by said lugs, a spring for holding said standard in position to bring 20 the wheel in contact with an opposing surface, and a gong arranged to be struck by

the hammer on the spring-wire, substantially as set forth.

4. An alarm comprising the base-plate C, weighted standard D, pivoted to said base-²⁵ plate and provided with the lug f, the spring E, arranged to act in conjunction with said lug, the friction-wheel G, journaled to the standard and provided with the lugs i, the spring-wire H, provided with the bends j k ³⁰ and carrying the hammer I, and the gong J, arranged to be struck by said hammer, substantially as set forth.

In testimony that I claim the foregoing I have hereunto set my hand, at Milwaukee, in ³⁵ the county of Milwaukee and State of Wisconsin, in the presence of two witnesses.

HERMAN WARLICH.
